CLAIM

I claim the ornamental design for board game, as shown and described.

DESCRIPTION

FIG. 1 is a top plan view of the packaging for the board game, shown broken away for ease of illustration;

FIG. 2 is a front elevational view of the assembled game and packaging thereof;

FIG. 3 is a perspective view thereof;

FIG. 4 is a folding container for the board game, shown broken away for ease of illustration;

FIG. 5 is a perspective view of the game pieces for the board game, shown broken away for ease of illustration;

FIG. 6 is a perspective view of the game board and game pieces;

FIG. 7 is a top view of the board for the board game, shown broken away for ease of illustration;

FIG. 8 is a perspective view of the board for the board game, shown broken away for ease of illustration;

FIG. 9 is a side perspective view thereof;

FIG. 10 is a side perspective view thereof;

FIG. 11 is another side perspective view thereof;

FIG. 12 is a side elevational view thereof;

FIG. 13 is a bottom perspective view thereof;

FIG. 14 is an enlarged view of the contours of the board game, shown broken away for ease of illustration;

FIG. 15 is another enlarged view of the contours of the board game, shown broken away for ease of illustration; and,

FIG. 16 is another enlarged view of the contours of the board game, shown broken away for ease of illustration.

The broken line showing is for illustrative purposes only, and forms no part of the claimed design.
